Primary Examiner—Jennifer Rivard

(74) Attorney, Agent, or Firm—Melvin I. Stoltz

(57) CLAIM

The ornamental design for the locking carrying/storage case for hair rollers, as shown and described.

DESCRIPTION

FIG. 1 is a perspective view of the locking carrying/storage case for hair rollers showing my new design;

FIG. 2 is a front elevational view thereof;

FIG. 3 is a side elevational view thereof, the opposite side being a mirror image thereof;

FIG. 4 is a top plan view thereof;

FIG. 5 is a bottom plan view thereof; and,

FIG. 6 is a rear elevational view thereof.

The broken line environmental showing is for illustrative purposes only and forms no part of the claimed design.
